(57) **ABSTRACT**

A new and distinct *Heuchera* plant characterized by leaves
which are multicolored changing from peach to gold with a
strong veil overall, medium size, lobed leaves, yellow green
flowers on short flowering stems, a medium mounding habit,
and excellent vigor.

1 Drawing Sheet

1

Botanical denomination: *Heuchera* hybrid.
Variety designation: 'Topaz Jazz'.

BACKGROUND OF THE INVENTION

The present invention relates to a new and distinct cultivar of *Heuchera* and given the cultivar name of 'Topaz Jazz'. *Heuchera* is in the family Saxifragaceae. *Heuchera* 'Topaz Jazz' originated as a controlled cross using *Heuchera* 'K873-2', a proprietary, unpatented, unnamed plant as the seed parent, and *Heuchera* 'K853-1', a proprietary, unpatented, unnamed plant as the pollen parent.

Compared to the seed parent, *Heuchera* 'K873-2', the new cultivar has a larger habit and the flowering stem attitude is upright rather than side-facing.

Compared to the pollen parent, *Heuchera* 'K853-1', the new cultivar has yellow green flowers rather than green and the leaves are veiled rather than not veiled.

Compared to *Heuchera* 'TNHEUCHA', U.S. Plant Pat. No. 27,567, the new cultivar has smaller leaves that are more lobed and undulate and a tighter habit with more crowns. The flowers of the new cultivar are yellow green rather than light salmon pink and are more upright growing.

Compared to *Heuchera* 'Ginger Ale', U.S. Plant Pat. No. 18,173, the new cultivar has a larger leaves, with a stronger white veil, and are more undulate in brighter colors. The inflorescences are shorter in the new cultivar and are not leafy as are the peduncles of 'Ginger Ale'.

This new *Heuchera* is uniquely distinguished by:

1. leaves which are multicolored changing from peach to yellow green with a strong white veil overall,
2. medium large, palmately lobed leaves,
3. yellow green flowers on upright short flowering stems,
4. a medium mounding habit, and
5. excellent vigor.

This new cultivar has been reproduced only by asexual propagation (tip cuttings and tissue culture using growing tips). Each of the progeny exhibits identical characteristics to the original plant. Asexual propagation in 2013 by cuttings and tissue culture using standard microppropagation

2

techniques with terminal and lateral shoots, as done in Canby, Oreg., shows that the foregoing characteristics and distinctions come true to form and are established and transmitted through succeeding propagations. The present invention has not been evaluated under all possible environmental conditions. The phenotype may change with variations in environment without a change in the genotype of the plant.

10 BRIEF DESCRIPTION OF THE DRAWINGS

FIG. 1 shows a nine-month-old plant of *Heuchera* 'Topaz Jazz' growing in the trial bed in September in Canby, Oreg.

FIG. 2 shows the same plant in February.

15 FIG. 3 shows the new cultivar in mid-summer in the trial beds in Canby, Oreg.

DETAILED PLANT DESCRIPTION

20 The following is a detailed description of the new *Heuchera* cultivar based on observations taken in April of one-year-old specimens growing in one gallon containers in a covered, unheated greenhouse in Canby, Oreg. Canby is Zone 8 on the USDA Hardiness map. Temperatures range from a high of 95° F. in August to an average of 32° F. in January. Normal rainfall in Canby is 42.8 inches per year. The color descriptions are all based on *The Royal Horticultural Society Colour Chart*, 5th edition, 2007.

Plant:

Form.—Basal rosette, herbaceous perennial.

Hardiness.—USDA Zone 4 to 9.

Size.—21 cm tall from top of the foliage to the ground and 38 cm wide.

Number of crowns.—10.

Habit.—Mounding.

Vigor.—Excellent.

Leaf:

Type.—Simple.

Arrangement.—Rosette.

Shape.—Broadly ovate to orbicular.

<i>Number</i> .—About 110.		<i>Flower bud</i> :
<i>Blade size</i> .—Grows to 11 cm long and 12 cm wide.		<i>Size</i> .—3 mm wide and 5 mm long.
<i>Venation</i> .—Palmate.		<i>Description</i> .—Glandular puberulent, ovoid, down facing.
<i>Lobing/division</i> .—7 palmate lobes, with shallow secondary lobes.	5	<i>Color</i> .—Yellow Green 151A.
<i>Margins</i> .—Crenate, mildly undulate.		<i>Flower</i> :
<i>Apex</i> .—Mucronulate.		<i>Type</i> .—Perfect.
<i>Base</i> .—Cordate, strongly overlapping and sometimes spiraling in.		<i>Shape</i> .—Campanulate.
<i>Surface texture</i> .—Glandular-puberulent on both sides.	10	<i>Attitude</i> .—Side-facing.
<i>Leaf rugosity</i> .—Absent.		<i>Size</i> .—5 mm long and 6 mm wide.
<i>Petiole description</i> .—Grows to 14 cm long and 3.5 mm wide, glandular hairs, Greyed Red 182B.		<i>Corolla description</i> .—5 petals, each 3 mm long and 1.3 mm wide, spatulate, 1-to 2-notched near tip, margins entire, tip acute, glandular-puberulent and White NN155A on both sides.
<i>Leaf color</i> .—Grows to 16 cm long and 2.5 mm wide, glandular hairs, Greyed Red 182B.	15	<i>Calyx description</i> .—Campanulate, 5 mm long and 6 mm wide, with 5 lobes with wide sinuses divided $\frac{1}{2}$ way to the base, each 2 mm wide and 3 mm long, oblong in shape, back side glandular-puberulent, glabrous inside, tip obtuse, margin entire, Yellow Green 151A on both sides.
<i>Leaf color</i> .—Variable, depending on light and temperature; spring topside, new leaves Greyed Orange 178B with a strong veil that covers all but veins and margins, closest to Greyed Orange 177C, bottom side Greyed Purple 185B, mature leaves Greyed Orange 165B and 165C with veins 165A, bottom side Greyed Orange 165C near margins then tinted 185B toward the center; summer and fall topside, Greyed Orange 167A to 161A on margins and veins with vein closest to 161D to Yellow Green 150D, bottom side Greyed Red 182C; winter topside closest to Greyed Red 182C with vein Greyed Purple 183B (lightning to Yellow Orange 19B with vein Greyed Red 179A), bottom side closest to Greyed Red 182C.	20	<i>Stamen description</i> .—5 in number, filaments 3 mm long, White NN155A, anthers 0.4 mm long, Orange 26A, no pollen.
<i>Inflorescence</i> :	25	<i>Pistil description</i> .—1, 2-beaked, 4 mm long and 2 mm wide, Yellow Green N144A overall, ovary 2 mm long and 2 mm wide, style 2 mm long.
<i>Size</i> .—Grows to 4.5 cm wide and 11 cm long.		<i>Fragrance</i> .—None.
<i>Type</i> .—Upright thyrs.		<i>Lastingness</i> .—Each thyrs blooms for about 3 weeks on the plant.
<i>Number of flowers per thyrs</i> .—About 150.		<i>Fruit and Seed</i> : None seed, infertile.
<i>Number of thyrs</i> .—About 20.	30	<i>Pest and disease tolerance</i> : The new cultivar is typical to the genus. No known resistances to pests or diseases. No problems have been found in Canby, Oreg.
<i>Peduncle</i> .—Grows to 28 cm long and 4 mm wide at base, glandular hairs, Greyed Red 178A.		I claim:
<i>Pedicel</i> .—Grows to 4 mm long, with glandular hairs, Yellow Green 152C.	35	1. A new and distinct <i>Heuchera</i> plant as herein illustrated and described.
<i>Bloom period</i> .—Spring to fall.	40	* * * * *
